Primary Examiner — Bridget L Eland*(74) Attorney, Agent, or Firm* — Mersenne Law(57) **CLAIM**

The ornamental design for a nasal dilator, as shown and described.

DESCRIPTION

FIG. 1 is a top plan view of a nasal dilator showing my new invention.

FIG. 2 is a perspective view thereof shown in an environment; and,

FIG. 3 shows a three-quarter perspective view thereof. The broken line showing of human facial features is for the purpose of illustrating environmental structure and forms no part of the claimed design.

The stylized letter "U" vertically overlapping a stylized letter "A" forming part of the claimed design is a registered trademark of Under Armour, Inc.
